UNITED STATES PATENT OFFICE.

DAVID BARNEY, OF GOLDEN, MONTANA, ASSIGNOR OF TWO-THIRDS TO ARTHUR BARNEY,
OF GOLDEN, MONTANA, AND CHARLES E. CHRISTOPHERSON, OF JOLIET, MONTANA.

BEET-LOADER.

No. 891,973.

Specification of Letters Patent.

Patented June 30, 1908.

Application filed June 4, 1907. Serial No. 377,201.

To all whom it may concern:

Be it known that I, DAVID BARNEY, a citizen of the United States, residing at Golden, in the county of Carbon and State of Montana, have invented a new and useful Beet-Loader, of which the following is a specification.

This invention relates to beet loaders and its object is to provide a wagon designed to be drawn over a field containing the loose beets and having mechanism whereby the beets can be collected and thrown into the wagon, the power produced by the rotation of one of the wheels of the wagon being utilized for operating the throwing mechanism.

Another object is to provide mechanism of this character which is adjustably connected to the wagon so that the same can be filled at the front and rear thereof as well as 20 at intermediate points.

A still further object is to provide simple and efficient means whereby the driver can quickly place the throwing mechanism into or out of operative relation with the power 25 wheel.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a side elevation of a beet loader embodying the present 35 improvements, the throwing mechanism being shown by dotted lines in raised position. Fig. 2 is a rear elevation of the throwing mechanism, the supporting roller thereof being shown in section. Fig. 3 is a plan view 40 of said mechanism. Fig. 4 is an enlarged section through the driving wheel and its shifting device.

Referring to the figures by characters of reference, 1 designates a wagon body supported by suitable running gear 2. Arranged longitudinally along one side of this body is a rail 3 fastened in any suitable manner to the ends of the body 1. One of the rear supporting wheels 4 of the device has 50 driving mechanism of novel construction connected thereto. This mechanism has been shown in detail in Fig. 4 where it will be seen that the same consists of a cap 5 designed to be placed over the outer end of 55 the hub of wheel 4 and formed with lugs or

projections 6 which project between the spokes of the wheel. The cap is designed to be fastened upon the head in any desired manner, as by means of a set screw 7 and extending from this cap is a stem 8 on which is 60 mounted a grooved wheel 9. A circular flange 10 extends from the cap and surrounds the hub 11 of wheel 9 and formed upon the cap of said hub are teeth 12 which are held normally out of engagement by means 65 of a spring 13 interposed between cap 5 and hub 11. A rounded projection 14 is formed upon the center of the outer face of wheel 9 and a block 15 is secured upon the outer portion of stem 8 and is similarly rounded. 70 Interspersed between the rounded portion 14 and the block 15 is a spreading device 16 in the form of a substantially wedge-shaped plate having a slot 17 through which the stem 8 projects. An operating rope 18 is 75 connected to the small end of the spreading device and extends to the front of the wagon where it is within convenient reach of the driver.

Mounted upon the rail 3 is a slide 19 having an inturned flange 20 designed to lap the bottom of the rail so as to prevent accidental displacement of the slide. This slide has an arm 21 pivotally connected to it and extending laterally therefrom and pivoted to 85 the lower end of the arm is a strip 22 constituting the head of the collecting device. Fingers 23 extend forward from this strip and constitute tines and an arm 24 extends upward from strip 22 close to its pivot 25 90 and has a guard rod 26 projecting forward therefrom and formed integral with the end tine or finger 23. Each of the fingers or tines 23 has an angular stem 27 which fits within the cross strip 22 and is preferably 95 held in engagement therewith by means of a retaining strip 28 suitably secured upon the strip 22. The tine which is farthest removed from the guard 26 is looped backward as shown at 29 in Fig. 1 so as to form 100 an outer guard to prevent the beets or other material which is upon the collector from slipping off the outer end thereof.

The lower end of arm 21 to which the strip 22 is pivoted is preferably forked as 105 shown in Fig. 3 and has a brace 30 extending therefrom and journaled in an ear 31 extending from slide 19. As the ends of this brace are rigidly connected to the strip 24 said brace constitutes means for preventing 110

the strip 22 from moving backward or forward under any pressure to which it might be subjected. An arm 32 extends upward from the forked end of arm 24 and secured to it is one end of an operating rope 33 which extends over a pulley 34 mounted in a standard 35 extending upward from slide 19. Said rope also extends downward and under a second pulley 36 carried by said standard 10 after which the rope is carried forward and over a pulley 37 connected to the front portion of the wagon. The end of the rope is then brought back and secured within the groove of wheel 9.

15 In using this device the slide 19 is first secured preferably at the front or the rear end of the body by inserting a pin 38 through the side and into one of a series of openings 39 in rail 3. The slide will therefore be locked 20 against movement upon the rail. It is of course to be understood that any other desired means may be employed for locking the slide if desired. When the parts have been secured in this manner the tines 23 are lowered 25 into contact with the ground and the wagon is then drawn forward so that beets or any other loose vegetable growths in the path of the flexible device will be gathered by the tines and between the guards 26 and 30 29. The rotation of wheel 4 will not cause the wheel 9 to revolve because said wheel is normally out of engagement with the cap 5. When the gathering device becomes filled and it is desired to deposit the contents 35 thereof in the body 1 the operator pulls forward on rope 18. This causes the wedge-shaped spreading device 16 to force the wheel 9 against the tension of spring 13 so that the teeth 12 upon said wheel will engage 40 the corresponding teeth on the cap. Wheel 9 will therefore be rotated and will wind the rope 33 thereon. An upward pull will therefore be exerted upon arm 32 and arm 21 will be swung upward. It will be noted 45 that the inner end of strip 22 projects past the fork of arm 21 as shown at 40 and therefore it is obvious that when arm 21 is swung upward strip 22 will be allowed a certain independent swinging movement in a 50 vertical plane until the projecting end 24 contacts with the arm 21. The further upward swinging movement of arm 21 will cause the collecting device to swing upward therewith and when arm 21 reaches an almost 55 vertical position the collecting device, which is made up of strip 22 and prong 23, will swing upon its pivot 25 so that the contents thereof will drop or be thrown into the body 1. It is of course to be understood 60 that this upward movement of arm 21 and the collecting device is very rapid and when the parts are brought to a sudden stop upon reaching the limit of their upward movement a throwing action will be produced and 65 the discharge of the contents of the collect-

ing device into the body 1 is therefore insured. As soon as the material has been discharged into the wagon body the operator releases the rope 18 and the spring 13 will therefore press the wheel 9 outward 70 against the spreading device and return the device to its initial position and at the same time release the wheel 9 from engagement with the cap. The weight of the collecting device and the parts connected thereto will 75 then cause the mechanism to return to its position upon the ground. The stopping of the upward movement of the arm 21 can be effected by a spring 41 upstanding from the slide 19 and this spring will also tend to 80 throw the parts backward to their initial positions when the wheel 9 is shifted out of engagement with cap 5. After the body 1 has been filled at one point the slide 19 can be adjusted longitudinally upon the rail and 85 can be again secured so that the gathered material can be deposited within the body at other points. The operation above described is repeated until the entire wagon body is filled.

90 It will be seen that the mechanism described, for collecting beets and depositing them in a wagon body can be readily connected to an ordinary wagon, it merely being necessary to fasten the rail 3 to the 95 wagon body and to attach the cap 5 to the hub of one of the wheels. The operation is very simple and said mechanism will be found thoroughly efficient for the purposes intended.

100 What is claimed is:

1. The combination with a portable receptacle; of a collecting device connected thereto and movable longitudinally thereof and disposed to ride upon the ground, and 105 means for swinging said device to direct the contents thereof into the receptacle.

2. The combination with a portable receptacle; of a gathering device connected thereto and suspended therefrom, said device 110 being movable longitudinally of the receptacle and means for lifting said device to direct the contents thereof into the receptacle.

3. The combination with a portable receptacle; of a gathering device suspended 115 therefrom and disposed to ride upon the ground, said device being movable longitudinally of the receptacle and means operated by the movement of the receptacle for lifting said device to direct the contents thereof into 120 the receptacle.

4. The combination with a portable receptacle; of a gathering device adjustably and pivotally connected thereto, said device being disposed to move upon the ground beside and longitudinally of the receptacle, and mechanism operated by the movement of the receptacle for swinging the collecting device above the receptacle to discharge the contents thereof.

5. The combination with a portable receptacle; of a gathering device pivotally connected thereto and suspended therefrom, said device being disposed to move upon the ground and longitudinally of the receptacle, and mechanism operated by the movement of the receptacle for lifting the gathering device to direct the contents thereof into the receptacle.
10. 6. The combination with a portable receptacle; of a pivoted arm adjustably connected thereto and normally suspended therebelow, a collecting device pivotally connected to the arm, and means for swinging the arm vertically to discharge the contents of the collecting device into the receptacle, said collecting device and its arm being movable longitudinally of the receptacle.
15. 7. The combination with a portable receptacle; of an arm pivotally connected thereto, and normally suspended therebelow, a collecting device pivotally connected to the arm and disposed to move upon the ground, and means operated by the movement of the receptacle for swinging the arm to bring the collecting device above the receptacle and in an inverted position.
20. 8. The combination with a portable receptacle; of an arm pivotally and slidably connected thereto and normally suspended therebelow, a strip pivotally connected to the arm, tines extending therefrom, guards extending from the strip, and means operated by the movement of the receptacle for swinging the arm to bring the strip and tines above the receptacle.
25. 9. The combination with a portable receptacle, and a rail secured thereto; of a slide upon the rail, means for securing the slide in adjusted position, an arm pivotally connected to the slide, a collecting device movably connected to the arm, and means operated by the movement of the receptacle for raising and inverting the collecting device above the receptacle.
30. 10. The combination with a portable receptacle and a guide rail secured thereto; of a slide adjustably mounted upon the rail, an arm pivotally connected to and normally depending from the slide, a strip pivotally connected to the arm, tines and guards extending from the strip and constituting a collecting device, and means operated by the movement of the receptacle for swinging the arm and collecting device above the receptacle.
35. 11. The combination with a wheel supported receptacle, a drive wheel, and manually operated means for placing the drive
- wheel in operative relation with one of the supporting wheels; of an arm pivotally connected to and normally suspended below the receptacle, a collecting device carried thereby, said device and its arm being movable longitudinally of the receptacle and means operated by the operating wheel for swinging the collecting device above the receptacle.
40. 12. The combination with a wheel supported receptacle; of a drive wheel, manually operated means for placing said wheel into operative relation with one of its supporting wheels, means for automatically disengaging the wheels, a guide rail upon the receptacle, a slide adjustably mounted thereon, an arm pivotally connected to the slide and normally depending therefrom, a gathering device connected to the slide, and means operated by the rotation of the drive wheel for swinging the gathering device above the receptacle.
45. 13. The combination with a wheel supported receptacle and a guide rail thereon; of a drive wheel, manually operated means for placing said wheel in operative relation with the supporting wheel, a slide upon the guide rail, an arm pivotally connected thereto and normally suspended therebelow, a collecting device pivotally connected to the arm, means operated by the drive wheel for swinging the arm and collecting device upward, and a yieldable stop for said arm.
50. 14. The combination with a wheel supported receptacle, a drive wheel, and manually operated means for placing said wheel in operative relation with one of the supporting wheels; of a guide rail upon the receptacle, a slide adjustably connected thereto, an arm pivotally connected to the slide and normally suspended below the receptacle, a collecting device upon the arm and disposed to move upon the ground, and means operated by the drive wheel for swinging the arm to invert the collecting device above the receptacle.
55. 15. The combination with a portable receptacle; of a collecting device adjustable in the direction of the movement of said receptacle, and means for actuating said device to direct the contents thereof into the receptacle.

In testimony that I claim the foregoing as my own, I have hereto affixed my signature in the presence of two witnesses.

DAVID BARNEY.
